United States Patent Office

Des. 227,664
Patented July 10, 1973

227,664

BUILDING

Donald Michael Genaro, Haworth, N.J., and Gordon Elliott Sylvester, Jamaica, N.Y., assignors to Bell Telephone Laboratories, Incorporated, Murray Hill, N.J.

Filed Dec. 29, 1971, Ser. No. 213,793

Term of patent 14 years

Int. Cl. D25—03

U.S. Cl. D13—1 R

FIG. 2

FIG. 5

FIG. 6

FIG. 7

FIG. 8

FIG. 1 is a perspective view of the front and left side of a building embodying our new design;

FIG. 2 is a perspective view of the front and left side of the building with a utility building attached;

FIG. 3 is a front elevation of the building shown in FIG. 1;

FIG. 4 is a rear elevation of the building shown in FIG. 1;

FIG. 5 is a left side elevation of the building shown in FIG. 1;

FIG. 6 is a right side elevation of the building shown in FIG. 1;

FIG. 7 is a front elevation of the building with attached utility building shown in FIG. 2; and

FIG. 8 is a left side elevation of the building with attached utility building shown in FIG. 2.

We claim:
The ornamental design for a building, substantially as shown and described.
